UNITED STATES PATENT OFFICE.

THOMAS W. H. MOSELEY, OF CINCINNATI, OHIO.

ATTACHING IRON ROOFING.

Specification of Letters Patent No. 23,600, dated April 12, 1859.

To all whom it may concern:

Be it known that I, THOS. W. H. MOSELEY, of Cincinnati, in the county of Hamilton and State of Ohio, have invented certain 5 Improvements in Iron Roofing, and that the following is a full, clear, and exact description of the principle or character which distinguishes it from all other things before known and of the usual manner of making, 10 modifying, and using the same, reference being had to the accompanying drawings, of which—

Figure 1 is a perspective view of the roofing. Fig. 2 represents one of the roofing 15 plates.

My invention consists in an improvement in iron roofing described and represented as follows:

Upon the rafters *a a*, which may be of 20 wood or iron, arched or straight, I secure by bolts or screws a series of iron chairs *c, c* of the form shown in Fig. 1. The dovetail opening in the chairs is so formed as to embrace the lower half of the iron rails or purlins *e, e*, and allow them to move with freedom 25 in the chairs. These chairs are at suitable distances apart in parallel rows upon the several rafters and the lower half of each purlin is passed through each series of 30 chairs. The purlins are formed alike above and below and a cross section would somewhat resemble the letter *I*, and is in fact what is termed in trade *I*-iron. To the under side of the roofing *m* which I prefer to 35 make of corrugated metal I attach by bolts or screws dovetail pieces of metal *n* of form corresponding to the form of the chairs and these pieces I call anchors. They are arranged in lines corresponding to the lines of

the chairs *c* and these anchors embrace the 40 upper flange of the purlins as shown in Fig. 1. The sheets of roofing are drawn over the purlins lengthwise and there is sufficient play left for the purlins in the dovetail openings of the anchors to accommodate the 45 expansion and contraction of the roofing, in the direction of the rafters, while the expansion and contraction in the direction of the purlins and the expansion and contraction of the purlins also are accommodated 50 to any extent by the freedom of motion of the purlins in the chains and anchors.

I have thus constructed a perfect metallic roofing of great strength and of the utmost simplicity both as regards the manufacture 55 of the several parts and the putting together, not a bolt or screw being required to secure the roofing plates and a roof which can never suffer from the greatest ranges of atmospheric temperature. 60

What I claim as my invention and improvements in iron roofing is—

1. Securing the metallic roofing to the ribs or purlins so that it may slide or move freely upon and in the direction of the length of 65 the purlins substantially as herein set forth.

2. I claim securing the purlins to the rafters of the building so that they may have freedom of motion in the direction of their length substantially as herein set 70 forth.

3. I claim the combination of the chairs *c*, double flanged rail *e*, anchors *n* and metallic roofing *m* as herein set forth.

THOS. W. H. MOSELEY.
